TYPEWRITING MACHINE

William A. Dobson, Wethersfield, Conn., assignor
to Underwood Elliott Fisher Company, New
York, N. Y., a corporation of Delaware

Application January 16, 1936, Serial No. 59,361

24 Claims. (Cl. 197—63)

This invention relates to typewriting machines, and especially to devices for expediting the setting of marginal stops to vary the length of the writing-line.

5 This invention is particularly adaptable to machines of the Portable class, which are used, generally for correspondence only, by unskilled, or non-professional operators. Social stationery varies greatly in size, and it is therefore desirable 10 to have margin-gaging means of great flexibility, so that the line-length may be easily and quickly adjusted to suit the size of the stationery and the length of the letter.

Generally, in such correspondence, the necessary line-indentations are limited to those for the date-line, paragraph-indentations, and signature-line, and by the use of suitable tabulator-stops to co-operate with the margin-gaging stops, the space-relationship of such constantly-recurring indentations may be maintained uniformly 20 regardless of the line-length selected.

It is a feature of this invention that the operator may select many different line-lengths without the necessity of setting the stops individually. To establish the writing-line, with even margin-lines on each side of the sheet, and simultaneously to establish the various indented positions, it is necessary for the operator only to insert the stationery around the platen in the 30 usual manner and move the carriage rightwardly to the desired left margin, which will be determined by the position of the printing-point, or type-guide position. A knob, conveniently placed at the rear of the carriage, is then turned as far 35 as it will go, and then fractionally turned in the reverse direction so that suitable detent-means may operate to secure the adjustment, and the machine is ready for operation. The paragraph-indentation, and date-and-signature-line indentations are automatically established without 40 further manipulation.

A line-end-signal device and a line-end key-lock are usually both controlled in relation to the setting of the right-hand margin-stop, which 45 comes into play at the finish of a line. An additional feature of this invention is that regardless of how the novel line-length-changing means are adjusted, such adjustment also assures that the signal and key-lock will function in proper 50 accord with the selected line-length.

In practicing this invention, a novel stop-shaft, with helically-threaded right and left end portions, and an unthreaded central portion, is journaled, preferably behind the platen, in the 55 carriage end-plates. The previously mentioned

adjustment knob is preferably located outside of the right-hand end-plate. The helical threads at each end of the stop-shaft are of opposite pitch. A pair of margin-stops of novel design, to establish left and right hand margins, are 5 threaded to co-operate with the left and right hand portions of the stop-shaft respectively, and are mounted thereon. A guide-rail, which is preferably graduated to serve additionally as a line gaging and centering scale, is mounted on 10 the rear plate of the carriage to co-operate with suitable key-ways formed in the margin-stops to prevent the rotation thereof.

The rotation of the adjustment knob by the operator thus causes the margin-stops to travel 15 laterally on the shaft, approaching or withdrawing from each other at an equal rate, depending on the direction of rotation of the knob. The margin-stops are arranged to co-operate with the usual non-traveling counter-stop, 20 whereby the letter-space travel of the carriage is arrested.

To establish paragraph-indentations, the left-hand margin-stop may be formed with an auxiliary stop-face carried to the right of the margin-stop face in such manner as to maintain 25 an indentation of one inch with respect to the left-hand margin-line, by co-operating with a tabulator counter-stop and carriage-release means of familiar and standard design.

For such deep indentations as the date and signature lines require, a separate tabulator-stop is slidably mounted on the unthreaded central portion of the stop-shaft, and adjustably connected to the right-hand margin-stop by a 35 rigid link or draw-bar. The lateral motion of the margin-stop thus projects or retracts the tabulator-stop equally, and the alignment of the date and signature lines is assured.

Obviously it is not necessary to restrict the 40 use of the tabulator-stops to paragraph or signature line indentations, as they can be used with equal facility in making simple columnar tabulations.

The device may be concealed from view by 45 housing it in the space formed by the rear plate of the carriage and the upper portion of the paper-table. The latter may be suitably hinged to be swung forward to permit reference to the scale, or inspection of the line-gaging device.

50 Other features and advantages will hereinafter appear.

In the accompanying drawings,

Figure 1 is a fragmentary perspective of a 55 typewriter of the portable class, illustrating the

novel margin-gaging means, the associated tabulator-stops, the coacting counter-stops, the carriage-escapement release and the line-lock mechanism.

5 Figure 2 is an elevation, showing the stop-shaft of Figure 1 in section, and an end view of the combination left margin-stop and paragraph-tabulator, and additionally illustrating the marginal counter-stop and the tabular counter-stop in inoperative and operative positions.

10 Figure 3 is a view similar to Figure 2, illustrating the tabulator-stop used for establishing signature-indentation.

15 Figure 4 is an end elevation of the machine of Figure 1, partly in section, showing a portion of the carriage, and additionally illustrating how the operative parts of the margin and tabulator stop mechanism are housed within the rear plate of the machine-carriage and the upper portion 20 of the paper-table.

20 Figure 5 is a diagrammatic representation of a typical typewritten letter.

25 Figure 6 is a diagrammatic representation of the cooperation of margin-stop and margin counter-stop to establish the left-hand writing margin.

30 Figure 7 illustrates, diagrammatically, the cooperation of the tabulator counter-stop and the paragraph-establishing stop-face of the left-hand margin-stop for establishing the paragraph-indentation.

35 Figure 8 illustrates the co-operation of the tabulator counter-stop and the intermediate tabulator-stop to establish the date-line and signature-line.

40 Figure 9 is a diagrammatic representation of right-hand margin-establishing means, illustrating the relation of end-of-line-signal to the key-lock, and additionally illustrating the operation of the end-of-line key-lock.

45 Figure 10 is a diagrammatic representation of a typewritten letter having a short writing line with marginal notations.

48 Figure 11 illustrates the camming action of the left-hand margin-stop as the carriage is returned to a new writing-line position after having been brought past the margin-stop to type a marginal notation.

50 Referring to Figures 1 and 4, 25 represents a portion of a carriage case-shift frame of a typewriter of the well-known Underwood Portable class, on which a laterally slideable carriage 26 is carried by means of the usual runways 27 co-operating with carriage-tracks 28 and anti-friction elements 30. A letter-feed rack 31 pivotally mounted on the carriage meshes with a pinion 32 coupled, as shown, to an escapement-wheel 33 co-operating with type-key-controllable escapement-dogs 34, 35 and a spring-motor and 55 tape 36, 37, to letter-feed the carriage 26. A platen 38 is revolubly mounted in a pair of carriage end-plates 40, 41. It will be understood that the actuation of a type-key, as 43, causes a type-carrier (not shown) to swing into printing 60 position against the platen 38.

65 The novel carriage-stop organization is as follows:

70 A helically-grooved stop-shaft 45 is journaled, in such manner as to prevent its lateral movement, in the carriage end-plates 40, 41, behind the platen 38. Shaft 45 has a portion of its left-hand end (as seen in Figure 1) formed with a square-cut right-hand thread or groove 46, and a portion of its right-hand end formed with a 75 similar, but left-hand, thread. The lead for

these threads is a suitable multiple of the letter-space pitch, say $\frac{1}{6}$ of an inch lead, or four times the usual letter-space pitch of $\frac{1}{6}$ inch. Four threads, $\frac{1}{6}$ inch apart, are cut in such case. The central portion of the shaft 45, occupying somewhat less than one-third of the total length, is left with a smoothly cylindrical surface of full diameter. At preferably the left-hand end-plate 41, shaft 45 is formed with a squared end 48 forming four lands to co-operate with a double-leaved spring-detent 50, carried on a suitable stud 51, to gage quarter turns of the shaft 45. At the right-hand end-plate 40, the shaft 45 may terminate in a suitable knob 52, by means of which the operator may manually rotate the 15 shaft to establish the margin-positions, as will later be described.

10 Formed to ride on shaft 45, Figure 1, and to be moved laterally by the rotation thereof, are a left-hand combination margin and tabulator stop 20 53, a right-hand margin-stop 54 and an intermediate, tabulator-stop 55. Stops 53 and 54 are formed with collars 56, threaded to co-operate with the threads on shaft 45. The collars 56, like the shaft 45, have four threads, as indicated 25 in section in Figures 2 and 3, to withstand the shock resulting from the sudden arrest of the carriage movement.

20 The left-hand stop 53, Figures 1 and 2, is formed with an extended integral rim 57, preferably concentric with the shaft 45 and cut away in the lower right quadrant to clear the frame-runway 27, as shown in Figure 4. The lower portion of said rim forms a stop-face 58 to co-operate with a margin counter-stop 59 of usual 30 design, for establishing the left-hand margin. A rightwardly-extending arm 60 on stop 53 terminates in a stop-face 61 for line indentation or tabulation purposes. The stop-face 61 is preferably so spaced with relation to face 58 to give 35 a one inch indentation of line from the established left-hand margin.

35 The right-hand margin-stop 54, Figures 1 and 4, has a similar rim 57, the lower part of which forms a stop-face 58 to co-operate with said 40 margin counter-stop 59 to establish the right-hand margin.

45 The margin counter-stop 59 is located intermediate of said margin-stops and, by suitable mechanism and control means later to be described in detail, co-operates with said margin-stops to arrest the carriage travel at the established line-margins.

50 The intermediate stop 55 is arranged to ride 55 slidably on the unthreaded central portion of the shaft 45, as shown in Figures 1 and 3, and includes a body 62 of suitable depth to give rigidity to the stop, and a face or rim 63 to coact with a tabulator counter-stop face 64 to establish deep line-indentations, such as a date-line or a signature-line, or intermediate, tabulated material. As shown in Figure 3, substantially the lower half of the face 63 is cut away to permit stop 55 to pass over margin counter-stop 59.

55 The rim-portions of the stops 53, 54 and 55 have a keyway 65 cut in the rear thereof, said keyway located in each stop in a horizontal radial line with respect to shaft 45, as indicated in Figures 2, 3 and 4. These keyways permit said rim-portions to embrace, as shown, a horizontal forwardly-extending line-gaging scale 66 which is 70 welded, or otherwise secured, to a rear plate 67 of the carriage 26.

75 It will be seen, therefore, that as the operator rotates the shaft 45 by means of the knob 52, 75

the stops 53 and 54, unable to rotate with shaft 45 because of the co-operation of the scale 66 with the keyways 65, must move laterally on the shaft, approaching or withdrawing from each other at an equal rate because of the oppositely threaded end-portions of the shaft. As shown in Figure 1, the intermediate stop 55 is rigidly but adjustably held in spaced relation to the right-hand margin-stop 54 by a bar 68 which is fastened, preferably by screws 70, to said stops. At each end of the bar 68, a series of holes 71 is provided to permit adjustment of the relative spacing of the two stops.

The stop 55 is therefore moved with the stop 54, and remains in definite relation thereto. The purpose of mounting stop 55 slidably on an unthreaded portion of the shaft 45 is to permit the ready adjustment of said stop with respect to stop 54, although such adjustment is seldom needed, as it has been found that an adjustment of stop 55, which will permit a two-inch writing-line, measured from the right-hand margin, is satisfactory regardless of the line-length as measured by the margin-stops 53 and 54.

To prevent any possibility of interference between the bar 68 and the left-hand margin-stop 53, the rim 57 of stop 53 is topped, as shown in Figures 1 and 2, permitting the bar 68 to pass over said rim without interference.

The operator, after feeding the stationery 72, Figure 6, around the platen 38 in the usual manner and centering the stationery on the platen, establishes the desired left and right hand margins, by moving the carriage 26 to the right until the desired left-hand margin-position is behind the printing-point, represented by a type-guide 73 in Figure 6. The knob 52 is rotated rearwardly, causing stops 53 and 54 to approach each other at an equal rate, because of the equally, but oppositely, threaded ends of shaft 45, stop 54 projecting tabulator-stop 55 before it. The extent to which the stops 53 and 54 can be moved is determined by the contact of stop 53 with counter-stop 59. At this point, the operator turns the knob forwardly a fraction of a revolution, until one of the faces of the square end 48 is grasped by the spring-detent 50.

In this simple manner, the left and right hand margins and the intermediate indentations, such as paragraph and signature indentations, are simultaneously established.

To begin the typing at the date-line, as is usually the custom, the operator depresses a tabulator-key 75, Figure 1, on the machine-keyboard, which, by familiar means later described, releases the carriage 26 from the control of the escapement-mechanism, and swings the tabulator counter-stop face 64 into the path of tabulator-stop 55, arresting the free leftward movement of the carriage at the desired point. The typewriting proceeds in the usual manner until the right-hand stop-face 58 engages the margin counter-stop face 59, arresting the letter-feed motion of the carriage. The engagement of contact-face 58 of the left-hand counter-stop 53 similarly establishes the left-hand margin of a new writing-line, as shown in Figure 6.

Should the carriage be at the extreme right position at which the counter-stop 59 is engaged with the left margin-stop 53, depression of the tabulator-key 75 will bring the counter-stop 64 into engagement with the paragraph-stop 61. For this reason, when it is desired to stop the carriage at the date-line, the typist may release the carriage so that same moves to the date-line de-

termining position, as defined by engagement of counter-stop 64 with tabulator-stop 55, by either of two modes of operation so as to avoid arresting the carriage by stop 61 engaging the counter-stop 64. In the first mode of operation, the carriage may be gradually released by repeated operation of the usual spacer-bar for a distance sufficient to move stop 61 beyond counter-stop 64, after which the carriage may be released for the remainder of the leftward movement by depressing the tabulator-key 75. The second mode of operation is that of merely depressing the tabulator-key twice, the first releasing the carriage to the paragraph-stop position defined by stop 61, the second depression of the tabulator-key releasing the carriage to the date-line position at which counter-stop 64 engages the tabulator-stop 55.

To indent for a paragraph, as shown in Figure 7, the carriage is moved to the extreme left-margin-position, and, by similarly depressing the tabulator-key 75, the carriage moves freely to the left, the tabulator counter-stop face 64 is brought into the path of the stop-face 61, and the carriage is arrested at the correct point. Similarly, the indentation for the signature-line may be quickly and accurately established through the co-operation of the tabulator counter-stop and the intermediate tabulator-stop 55.

The possibility of accidental rotation of the stop-shaft 45, resulting from the lateral reaction of the gaging stops at the moment of arrest of carriage travel, is precluded by the power of the spring-detent 50, supplemented by the friction engendered between the respective threads of the stop-shaft and both margin-stops.

As will be seen in Figures 1 and 6, the tabulator counter-stop face 64 is normally out of the path of the various margin and tabulator stop-faces. Said face 64 is brought into the path of the tabulator stop-faces by known means, in which the depression of the tabulator-key 75 rotates an associated key-lever 76 clockwise of Figure 1, about a suitable fixed pivot 77, and draws forward a U-shaped slide 78, pivotally secured to lever 76 at 80, and slidably mounted on a fixed bracket 81 by means of a slot-and-screw arrangement 82, 83. The forward motion of slide 78, through the intermediary of a cam-slot 84 formed in an obliquely upstanding arm 85 of the slide 78, and a pin 86 on an actuating lever 87, rotates said lever forwardly about a fixed pivot 88, which is carried by a lug 90 of a bracket 91, rigidly secured to a rear plate 92 of the case-shift frame 25. The actuating lever 87 projects rearwardly and upwardly through a slot 93 in plate 92, as shown in Figure 1.

A tabulator counter-stop lever 94, which at its left end terminates in the stop-face 64, is pivoted, intermediate its ends, to the upper side of the rear carriage-runway 27, by a screw 95. The right end of said tabulator counter-stop lever 94 is offset downwardly and projects to the rear at 96, Figure 1. An opening or fork 97 is provided at said rear projection 96 to receive the free upper end of the actuating lever 87, the forward motion of which causes the counter-stop face 64 to swing rearwardly and downwardly, as shown in dotted lines in Figures 1, 2 and 3, into the path of a tabulator-stop.

To simultaneously free the carriage 26 from the letter-feed escapement-mechanism, the slide 78 coacts with release means, as follows: The front surface 98 of the arm 85, Figure 1, engages and rotates a bell-crank lever 100, pivotally mounted on the bracket 91, and by a rigid link 101 also

rotates a bell-crank 102 pivoted, as it 103, to a suitable support, not shown. The leftward or free end of bell-crank 102 is provided with a freely revoluble roller or idler 104, which is normally lightly in contact with the feed-rack 31. The rotation of said bell-crank 102 thereby swings the rack 31 rearwardly, against the tension of a spring 105, about suitable pivots 106 at the carriage end-plates 40, 41, bringing said rack out of mesh with the pinion 32 and permitting the spring-motor 36 to draw the carriage 26 to the left until such motion is arrested by the coacting tabulator-stops and tabulator counter-stop.

On the release of the tabulator-key 75, a spring 107, secured to the machine-frame (not shown) and to a downward extension 108 of the tabulator key-lever 76, returns said key to its normal position against a bumper 109 in a front frame-plate 110, and permits the tabulator counter-stop lever 94 and carriage-rack 31 to resume their normal positions.

For whatever line-length is established by the rotation of the knob 52, it is desirable that the usual line-end signal be given at the customary distance from the end of the line, and that the determination of the right-hand margin-line be forced by a positive line-end key-lock.

To this end a finger 115, Figure 1, having a tip carried normally in the path of the margin-stops 53 and 54 is pivotally mounted, several letter-spaces to the right of the margin counter-stop 59, on a bell-crank 116, pivoted to the rear plate 92 of the shift-frame 25, as at 117. The downward arm 118 of bell-crank 116 terminates in a striker 120 which is normally held within, and against the edge of, a suitable bell 121, by the action of a tensile spring 122, joining said arm 118 and a downward extension 123 of a margin counter-stop slide-lever 124. As shown in Figure 1, finger 115 may not rotate leftwardly with relation to bell-crank 116, and therefore, as the stop-face 58 of right margin-stop 54 contacts said finger near the end of the writing-line, the bell-crank 116 is rotated about pivot 117 against the tension of spring 122. As the typewriting continues, and the stop 54 overrides finger 115, the bell-crank 116 will be freed to assume its normal position, and the spring 122 will cause the striker 120 sharply to hit the bell, signaling the approaching line-end.

Margin counter-stop 59, formed at the right end of counter-stop slide-lever 124, is held in the path of the margin-stops 53 and 54 through the action of the spring 122 which draws lever 124 rightwardly to the limit of slot 125 through which lever 124 is pivotally and slidably mounted to the rear of carriage shift frame 25 by a headed screw 126, and rotates the right end upwardly about said screw, such rotation being limited by the slideable contact of the left end of lever 124 with a rearwardly-extending arm 127 of a bell-crank 128. As shown in Figure 1, the left end of lever 124 is formed with a flange 130 and a guide-slot 131, to embrace the upper portion of a pendent lever 132, pivoted at the rear of plate 92.

As the typing continues after the line-end signal, the counter-stop lever 124 is driven leftwardly by the engagement of right-hand stop-face 58 with the counter-stop 59. Flange 130 contacts the lever 132 and rotates it, counterclockwise of Figure 1, about its pivot 133. The lower end of lever 132 causes the rotation of a bell-crank 134, suitably pivoted to the machine-frame at 135. The bell-crank, through the agency of a yieldable link 136, causes a key-locking ball 137 to be swung,

against the tension of a spring 138, under a locking shoulder 140 with which each key-lever 141 is formed, preventing the actuation of said key-levers. The line-lock action is diagrammatically shown in Figure 9, which additionally indicates the usual relationship between the bell-signal and key-locking positions.

If it should be found necessary to complete a word before a new line is started, the key-lock may be released by pressing a margin-release button 142, Figure 1, which projects through the machine front plate 100 and is connected at its back, by means of a stiff push-rod 143 to a lower arm of the bell-crank 128. Said bell-crank is thus rotated against the power of a coiled spring 144, and causes the rear arm 127 of said bell-crank to lift or swing the left end of the lever 124 upwardly about its pivot-screw 126. This depresses the counter-stop 59 below the path of the margin-stop 54, and the spring 122 pulls the counter-stop lever 124 to the right. The pendent lever 132 thus is relieved of its operating force, and the spring 138 swings the ball 137 out of locking arrangement with the key-levers 141 which may then again be operated to type the desired character. The spring 138 also returns the bell-crank 134 and pendent lever 132 to normal position. On the removal of pressure from the button 142, the coiled spring 144 returns the bell-crank 128 to normal position.

The button 142 may also be used to render the left-hand margin-stop 53 similarly ineffective for the left-hand margin-line, when it is desired to make left-hand marginal notations, as shown in Figure 10.

As shown, especially in Figures 1 and 11, the rear of the stop-faces 58 of margin-stops 53 and 54 are beveled to cam the counter-stop 59 downward, so that when the carriage has been permitted to travel past the counter-stop 59, through the action of the margin-release button 142, it may be returned either to the right or the left without additionally pressing button 142.

As clearly shown in Figure 4, the stop-shaft, the margin and tabulator stops and their associated counter-stops, are housed in, and protected by, the rear plate 67 of the carriage and an upper section 145 of a paper-table 146. The section 145 may be pivoted at end-plate 41 on an extension 147 of stud 51, and similarly pivoted at end-plate 40, to permit the section to be rotated forwardly to permit the operator to read the line-gaging scale 66, or to adjust the relative spacing between stops 54 and 55.

Variations may be resorted to within the scope of the invention, and portions of the improvements may be used without others.

Having thus described my invention, I claim:

1. In a typewriting machine, the combination of a laterally slidable carriage, margin-gaging means comprising a threaded shaft revolvably mounted in said carriage, means for rotating said shaft, a plurality of pairs of stops mounted on said shaft, the respective pairs of stops being arranged to approach or withdraw from each other depending on the direction of rotation of said shaft, key controllable means to govern the movement of said carriage, and a counter-stop arranged to be placed in the path of certain of said first-mentioned stops to arrest the carriage travel at a predetermined point.

2. In a typewriting machine having a frame, a laterally slidable, power-driven carriage mounted thereon, and key-controllable means to govern the movement of said carriage, margin-gaging

means comprising the combination of a threaded shaft revolvably mounted in said carriage, a plurality of margin-stops mounted on said shaft and arranged to be laterally adjusted with respect to each other by the rotation of said shaft, and counter-stops arranged in the path of the margin-stops to arrest the carriage travel at a predetermined point.

5. In a typewriting machine having a laterally 10 slideable, power-driven carriage and key-controllable means for governing the movement thereof, line-gaging means comprising the combination with a stop-shaft, having an unthreaded central portion and oppositely threaded end-portions, 15 margin-stops mounted on said end-portions and arranged to move laterally on said shaft by the rotation thereof, and an intermediate stop slidably mounted on said central portion and adjustably secured to one of said margin-stops so as to 20 be moved therewith, of margin-gaging and tabulator counter-stops arranged to co-operate with said shaft-stops to arrest the travel of said carriage.

4. In a typewriting machine having a laterally 25 slideable carriage, margin-gaging means comprising the combination of a left-and-right threaded stop-shaft revolvably mounted in said carriage, a plurality of margin-gaging stops therefor, with a counter-stop arranged in the path of said stops 30 to arrest the carriage travel at a predetermined point, each margin-gaging stop having a threaded portion to co-operate with said stop-shaft, and means co-operating with a fixed trackway to prevent the rotation of said stops in relation to the 35 stop-shaft.

5. In a typewriting machine having a laterally 40 slideable carriage, a pair of margin-stops, means mounting said margin-stops and manually operable for simultaneously adjusting said margin-stops toward or from each other to different positions lengthwise of the carriage for establishing a desired line-length, a counter-stop located intermediate of said margin-stops to arrest the carriage travel at the desired marginal positions, and means operable to withdraw said counter-stop from the path of said margin-stops to permit the carriage to travel beyond the previously 45 established marginal positions, said margin-stops and counter-stop being relatively arranged to permit the return of the carriage within the established line limits without additionally manipulating the counter-stop withdrawal means.

6. In a typewriting machine having a laterally 50 slideable carriage, a revolvable, screw-threaded stop-shaft journaled in said carriage, a pair of screw-threaded margin-gaging stops carried on said shaft, an auxiliary stop mounted on said shaft in adjustable spaced relationship to one of the margin-stops, means for rotating said stop-shaft, and means including a fixed guideway 55 mounted in said carriage in horizontal relationship to said stop-shaft and arms formed on said stops to slidably embrace said guideway to prevent the rotation of the stops as the stop-shaft 60 is rotated, and thus enforce a lateral movement of said stops.

7. The combination with a letter-feeding 65 typing-machine carriage, a carriage-return stop adjustable along said carriage, and a co-operative counter-stop, of a line-indenting stop carried by said carriage-return stop for concurrent adjustment therewith, a normally retracted counter-stop associated with said line-indenting stop, and a line-indenting key operable subsequently to the 70 carriage-return operation, said key being con-

nected and operable to release the carriage for consequent automatic movement in letter-feed direction and to concomitantly move said retracted line-indenting counter-stop into position to coact with the line-indenting stop on the carriage-return stop to limit said automatic movement for line-indenting; whereby adjustment of said carriage-return stop to any carriage-return-limiting position automatically provides, without any additional adjustment, for effecting line-indenting, by means of said key, with reference to said position.

8. In a typewriting machine, the combination with a letter-feeding carriage, of a pair of right and left margin-stops, an intermediate line-indenting stop, counter-stop means co-operative with said margin-stops and intermediate stop, and stop-setting means including a single manually-operable line-length regulator and connections operatively conjoining said regulator and 10 said stops and arranged so that manual operation of said single regulator shifts said margin-stops in unison either toward or from each other, depending on the operation of said single regulator, to determine both margin-positions of the 15 carriage simultaneously for different line-lengths, and concomitantly shifts the intermediate stop to keep the latter at a predetermined distance 20 from one of said margin-stops.

9. In a typewriter, the combination of a frame, 25 a laterally movable carriage mounted thereon, counter-stop means mounted on said frame in substantially fixed relation to said carriage, laterally adjustable right and left margin-stops and an intermediate stop mounted in said carriage to co-operate with said counter-stop means for margin-gaging and intermediate tabulating, and a single screw-threaded spindle connected to said margin-stops and arranged relatively thereto, so that rotation of said spindle adjusts said 30 right and left margin-stops in relation to said counter-stop means, said intermediate stop moving in unison with one of said margin-stops.

10. In a typewriter, the combination of a frame, 35 a laterally movable carriage mounted thereon, counter-stop means mounted on said frame in substantially fixed relation to said carriage, laterally adjustable right and left margin-stops and an intermediate stop mounted in said carriage to co-operate with said counter-stop means for margin-gaging and intermediate tabulating, a single screw-threaded spindle connected to said 40 margin-stops and arranged relatively thereto, so that rotation of said spindle adjusts said right and left margin-stops in relation to said counter-stop means, and detent-means applied to said single spindle to assure the adjustments of all of said stops, said intermediate stop moving in unison with one of said margin-stops at predetermined steps of adjustment.

11. In a typewriting machine having a frame, 45 a laterally movable letter-feeding carriage mounted thereon, and key-controllable means to govern the movement of said carriage, margin-gaging means comprising the combination of right and left margin-stops, stop-shifting mechanism, including a line-length regulator, operable by manipulating said regulator for shifting said stops in unison toward or from one another, and counter-stop means arranged to co-operate with 50 said margin-stops to arrest the carriage travel at a predetermined point.

12. In a typewriting machine having a frame, 55 a laterally slideable, power-driven carriage mounted thereon, and key-controllable means to govern 60

- the movement of said carriage, margin-gaging means comprising the combination of a stop-shaft, a pair of right and left margin-stops carried on said shaft, means including a stop-engaging screw-thread on said shaft for causing lateral adjustments of said stops in unison toward or from each other by rotations of said shaft, and counter-stop means to co-operate with said margin-stops to arrest the carriage.
13. In a typewriting machine, right and left margin-stops adjustable to different positions lengthwise of the carriage for gaging the start and end of a line with reference to a certain width and position of a work-sheet, a counter-stop, means, having a finger-piece, operatively connected to said margin-stops and operable by manipulating said finger-piece to shift said margin-stops in unison toward or from the counter-stop to gage both margin-widths of the work-sheet for different line-lengths, and a member operable by a margin-stop to signal the approach of the carriage to the end of a line, said margin-stop arranged to operate said signal-member at substantially uniform distances from the ends of the lines established by said means.
14. In a typewriting machine having types and a letter-feeding carriage, the combination of a pair of margin-stops, means, having a finger-piece, operatively connected to said margin-stops and operable by manipulating said finger-piece to shift said margin-stops in unison toward or from each other to establish a variety of writing-line lengths, counter-stop means to co-operate with said stops in margin-gaging, and type-controlling line-lock means controlled by one of said margin-stops to enforce the margin-gaging determination regardless of the length of writing-line selected.
15. In a typewriting machine, the combination of a letter-feeding reciprocating carriage, right and left line-end-defining carriage-stops, and stop-shifting mechanism including a single manually-operable line-length regulator, and a device operable, by manipulating said single regulator, to shift said carriage-stops laterally along the path of carriage travel so as to variably predetermine both the right and left line-end positions of the carriage simultaneously in varying the line-length settings of said stops.
16. In a typewriting machine, the combination of a letter-feeding reciprocating carriage, right and left line-end-defining carriage-stops, and stop-shifting mechanism including a single manually-operable line-length regulator, and a device operable, by manipulating said single regulator, to shift said carriage-stops laterally along the path of carriage travel so as to variably predetermine both the right and left line-end positions of the carriage simultaneously in varying the line-length settings of said stops; and an intermediate line-indenting stop, having a connection to one of said stops so as to be shifted along with the latter.
17. In a typewriting machine, the combination of a letter-feeding reciprocating carriage, right and left line-end-defining carriage-stops, and stop-shifting mechanism including a single manually-operable line-length regulator, and a device operable, by manipulating said single regulator, to shift said carriage-stops laterally along the path of carriage travel so as to variably predetermine both the right and left line-end positions of the carriage simultaneously in varying the line-length settings of said stops; and an intermediate line-indenting stop, having a connection to one of said stops so as to be shifted along with the latter, said connection being arranged for varying the distance between said intermediate line-indenting stop and said one stop for predetermining line-indentations of different extent.
18. The combination with a slidably mounted typewriter-carriage, of a pair of margin-stops, left and right, a line-length regulator, means connecting said regulator and margin-stops, and operative for shifting said margin-stops in unison toward or from each other to different positions along the range of carriage travel by the manipulation of said regulator, a counterstop to cooperate with each margin-stop, a secondary stop associated with each margin-stop to be moved therewith, and a counter-stop to co-operate with each secondary stop, for tabulating.
19. In a typewriting machine, the combination with a letter-feeding carriage, of right and left hand margin-stops for said carriage, counter-stop means for co-operating with said margin-stops, and coacting margin-regulating screws having a common single finger-piece, for varying both left-hand and right-hand margins by effecting opposite relative adjustments concomitantly between said margin-stops and said counterstop means.
20. In a typewriting machine, the combination with a letter-feeding carriage, of right and left hand margin-stops adjustable in respect to said carriage, threaded means common to said margin-stops for effecting simultaneous opposite adjustment thereof to establish various writing-line lengths, a tabulating stop connected to one of said margin-gage stops for adjustment therewith, and counterstops for said margin-gage and tabulating stops.
21. In a typewriting machine, the combination with a letter-feeding carriage, of right and left hand margin-stops for said carriage, a counterstop for co-operating with said margin-stops, coacting margin-regulating screws having a common single finger-piece, for varying both left-hand and right-hand margins by effecting opposite relative adjustments concomitantly between said margin-stops and said margin-counterstop, a paragraphing stop fixed to one of said margin-stops for concomitant screw adjustment, and a second counterstop for cooperating with said paragraphing-stop.
22. In a typewriting machine, the combination with a letter-feeding carriage, of right and left hand margin-stops for said carriage, a counterstop for co-operating with said margin-stops, coacting margin-regulating screws having a common single finger-piece, for varying both left-hand and right-hand margins by effecting opposite relative adjustments concomitantly between said margin-stops and said margin-counterstop, a paragraphing stop fixed to one of said margin-stops for concomitant screw adjustment, a deep indentation stop connected to the other of said margin-stops for concomitant adjustment therewith, and a second counterstop for cooperating with said paragraphing and indentation stops.
23. In a typewriting machine, the combination with a letter-feeding carriage, of right and left hand margin-stops for said carriage, a counterstop for co-operating with said margin-stops, coacting margin-regulating screws having a common single finger-piece, for varying both left-hand and right-hand margins by effecting opposite relative adjustments concomitantly between said margin-stops and said margin-counterstop,

a paragraphing stop fixed to one of said margin-stops for concomitant screw adjustment, a deep indentation stop connected to the other of said margin-stops by an adjustable connection to vary the setting of said deep indentation stop independently, and a second counterstop for cooperating with said paragraphing-stop and said indentation-stop.

24. In a typewriter having a laterally slidable carriage, margin-gaging and tabulating means

comprising a screw-threaded shaft rotatably mounted, margin-gaging stops threaded carried on said shaft for movement in unison toward or from each other by appropriate rotation of said shaft, tabulator stops slidably carried on said shaft, means preventing rotation of all of said stops, and means connecting each tabulator-stop with the respective margin-gaging stops for corresponding movement therewith.

WILLIAM A. DOBSON. 10
